UNITED STATES PATENT OFFICE.

TORBJORN CONRAD KORSMO, OF MADISON, WISCONSIN, ASSIGNOR TO MADISON-KIPP CORPORATION, OF MADISON, WISCONSIN, A CORPORATION OF WISCONSIN.

DIE-CASTING MACHINE.

Application filed June 28, 1926. Serial No. 119,143.

This invention relates to die casting machines and more especially to those in which the molten metal is injected into the die by air under pressure.

5 In prior art machines the molten metal is usually contained in a pressure chamber or goose neck to which air is admitted through a valve from a pressure line. The quantity of air admitted and the rate of admission 10 are not subject to as close control as is desirable, and one of the prime objects of the present invention is to secure such control in a simple and practical manner.

In a prior application, Serial No. 13,543, 15 filed March 6, 1925, there is described and claimed a machine in which the air under pressure is furnished by a spring urged piston, which is set or stressed during the closing movement of the dies by the die 20 actuating mechanism and released after the dies are closed.

The more important features of novelty 25 described herein are applicable to such a machine, but in order to develop additional features of novelty, the invention will be here described as embodied in a new type of machine, in which air from a pressure line is admitted and exhausted to move a piston or abutment, and this abutment by its movements displaces the air which acts directly 30 on the molten metal.

Viewed from a somewhat different angle, 35 the piston serves as a limiting partition, which controls the quantity of air admitted to act against the metal, and prevents cold air from the supply line from flowing into contact with the molten metal. By controlling the rate of movement of the piston, and by controlling the air displacing action of the piston, it is possible so to determine the 40 flow of metal to the die as to secure the best effect, and consequently freedom from blow holes and like defects.

Certain features of novelty herein 45 described may also be used in those machines in which air from a supply line acts directly on the molten metal, and no necessary limitation to use with the particular machine herein described is implied as to such features.

The preferred embodiment of the invention is illustrated in the accompanying drawings, in which,

55 Figure 1 is a side elevation of the machine with the driving motor and controlling

clutch mechanism broken away. The dies are shown closed and the piston has completed its working stroke.

Figure 2 is a plan view of the same.

Figure 3 is an enlarged plan view of the 60 cylinder and piston mechanism with parts broken away to show the construction. The piston is shown at the start of the working stroke.

Figure 4 is a fragmentary view, part in 65 elevation and part in vertical section, showing the inlet valve mechanism open (at the start of the piston's working stroke).

Figure 5 is a fragmentary view in section 70 showing the exhaust valve mechanism closed (during the working stroke).

Figure 6 is a section on the line 6—6 of Fig. 5.

Figure 7 is a view similar to Fig. 3, but 75 showing the parts in the positions assumed when the dies are open but moving toward closed position.

Figure 8 is a view similar to Fig. 4 but showing the parts in the position of Fig. 7.

Figure 9 is a section on the line 9—9 of 80 Fig. 8.

Figure 10 is a fragmentary vertical axial section showing the position of the parts when the dies are wide open.

Figure 11 is an enlarged fragmentary 85 section of the upper end of the goose neck and the bleed valve.

Figure 12 is an enlarged transverse section on the line 12—12 of Figure 10.

In order to disclose the invention fully it 90 is necessary to describe it in combination with dies and die actuating mechanisms. Devices described and claimed in Patent No. 1,590,246, dated June 29, 1926, and prior application Serial No. 86,285, filed February 5, 1926, have been chosen for this purpose. For this reason such devices are not claimed herein.

In the use of the machine it is at times 100 necessary to withdraw the dies from proximity to the melting pot, for example to change or adjust dies, or change melting pots. For this reason, the die guiding and actuating mechanism is mounted on a carriage which is bodily shiftable on occasion 105 along guides forming parts of the base.

A plurality of base members 15 carry two parallel guide bars 16 on which the carriage structure above mentioned is mounted. The rods 16 are shown broken away at the right 110

hand end in Fig. 1. In the machine as constructed they extend further and carry a motor and clutch supporting cradle. This, however, is not a part of the present invention 5 and is omitted to simplify the drawing. In the complete machine, therefore, there are additional base members 15 to carry the extending portions of the rods 16, and this extension is sufficient to permit the carriage 10 to move to the right a distance approximately equal to the interval between the base members 15 shown in Fig. 1.

A housing 17 is provided with lugs 18 which embrace and are slidable upon the 15 rods 16. Spaced from the housing 17 and also slidable on the rods 16, is a yoke 19 which carries a so-called "hot plate" 20. The hot plate is a support on which the fixed die part 23 is removably mounted. The hot 20 plate 20 is connected with the housing 17 by means of four guide bars 21, the guide bars serving as means to support and guide the movable die carrier 22, on which the movable die part 24 is removably mounted. 25 Thus the yoke 19 and housing 17 are connected together by the bars 21 to form a carriage structure which is slidable bodily from its normal position shown in Fig. 1 to the right, and the effect of such motion is to 30 carry the hot plate 20, the die carrier 22, and the related actuating mechanism bodily to the right away from the melting pot, which will shortly be described.

The housing 17 encloses a worm wheel 25, 35 which is driven by a worm 26 also enclosed in the housing 17. The worm is mounted on a shaft 27 and is driven by an electric motor through a clutch mechanism, both mounted to the right of the housing 17, and both 40 omitted from the drawings, as already explained.

The worm wheel 25 is mounted on a shaft 28 which extends out of the housing 17 and carries at its opposite ends parallel 45 cranks of equal radius; these cranks are indicated by the reference numeral 29, and each has a crank pin 30 and a cam 31, the cam being preferably formed integral with the crank. The identical connecting rods 32 50 are provided each with a longitudinal slot 33 in its swinging end, and this slot receives the corresponding crank pin 30. Adjacent the inner end of each slot 33 is a follower roller 34 which coacts with the periphery of the corresponding cam 31. The other end of 55 each rod is connected by a wrist pin 35 with a corresponding block 36 which guides the wrist pin 31 in a right line passing through the axis of the shaft 28.

60 The cams 31 are identical and symmetrical with reference to lines radial with respect to the axis of the shaft 28. One portion of the periphery of each cam is arcuate and concentric with the crank pin 30. When this 65 portion of the cam coacts with its follower

roller 34 crank pin 30 is confined in the outer end of slot 33 and a simple crank and connecting rod drive exists between the shaft 28 and each block 36. The remaining portion of each cam 31 is so formed that, coacting 70 with the follower roller 34, it moves the crank pin 30 in the slot 33 at such a rate as to neutralize the effect of the crank pin's motion on the block 36. Consequently, while the cranks 29 swing with the rollers 34 in 75 contact with the so called "dwell portions" of the cams, the blocks 36 stand at rest.

It will be observed also that the transition from the dwell portion of the cams to the arcuate portion is sudden and that therefore 80 the blocks 36 are reciprocated simultaneously with approximately harmonic motion but come suddenly to rest in the inward motion, dwell, and then suddenly start to move outward. The blocks 36 are connected to actuate 85 the movable die part and also certain other timed portions of the mechanism. This cam mechanism and the operation of the die part so that it has a sudden opening movement are claimed features in certain of the prior 90 applications above identified.

The crank connecting rod and cam mechanisms are strict duplicates, as has been suggested, and operate strictly in phase with each other. Each of the blocks 36 is fixed on a corresponding rod 37 and adjustable thereon by means of clamping nuts 38. The rods are guided in bearings 39 mounted on the housing 17 and in bearings 40 mounted on the yoke 19. They project to the left beyond the bearings 40 in order to actuate related mechanism hereinafter described. They pass through guide bearings 41 on the die carrier 22 which they operate positively in an opening direction, and yieldingly in a 10 closing direction. The positive opening engagement is through a pair of nuts 42 which are threaded on the rods 37 and which are locked together in the manner of check nuts. One of these directly engages bearing 41. 11 The yielding engagement is through springs 43 which are seated against a pair of check nuts 44 also threaded on the corresponding rods 37.

115 Mounted between the leftmost base members 15 is a furnace chamber indicated generally by the reference numeral 45 having heating means diagrammatically illustrated at 46. Any type of furnace and any type of heating means might be used.

120 Resting in the top of the furnace chamber 45 is a melting pot 47 which is bodily removable.

125 It will be observed that in the leftmost position of the yoke 19 and housing 17, the die parts 23 and 24 are above the right hand end of the melting pot 47 in position to be engaged by the goose neck hereinafter described.

130 Beyond the furnace chamber 45 and

aligned with the base members 15 are two supports 48, each of which has at its upper end a lug 49, through which a corresponding hinge pin 50 is inserted. Straddling the lug 49 of each base member 48 are pairs of lugs 51 on each side of a base casting 52. By withdrawing either hinge pin 50 the base casting 52 may be swung around the remaining pin 50. The member 52 carries the cylinder 53 and the effect of such action is to shift the cylinder laterally out of the way of the melting pot 47 when this is to be withdrawn.

The cylinder 53 has two depending lugs 54 and 55 which straddle the base member 52 and which are slidable on a rod 56 fixed in the base member 52 and in an upstanding lug 57 spaced therefrom. A spring 58 urges the cylinder to the right, and a stop screw 59 limits the motion under the urge of the spring. By turning the screw 59 it is possible, therefore, to adjust the cylinder in the direction of its axis, and this adjustment is useful to position the end of the goose neck relatively to the die.

The goose neck is shown at 60 and is pivoted at 61 to a bracket formed on the forward end of the cylinder. The end of the goose neck is formed with a nozzle 62 which coacts with a recess in a shiftable nozzle plate 63 pivoted at the lower side of the fixed die part 23. The nozzle plate 63 is formed with a recess and a communicating through port, as is clearly shown in Figure 10, and seats against the lower face of the two die parts 23 and 24, after these are closed together, with the through port in the nozzle plate 63 in registry with the sprue hole in the die, and the nozzle 62 in the recess and in registry with the through port.

Consequently, the adjustment effected by the screw 59 is such as to establish the proper relation between the nozzle 62 of goose neck 60 and the recess in the nozzle plate 63.

The goose neck is actuated by a vertically movable cross head 64 with which it is releasably connected. This releasable connection consists of an upward extension 65 on the goose neck, which has laterally extending trunnions 66 (see Fig. 12). The cross head 64 is formed with a vertical slot 67 having lateral extensions 68 in which the trunnions 66 engage. Consequently, in the normal position of the parts the vertical motion of the cross head 64 is imparted directly to the goose neck 60. The cross head 64 is carried by the yoke 19 and when this is withdrawn to the right the cross head 64 moves with it and automatically releases the goose neck 60.

The cross head 64 is guided on the back of the hot plate 20. On the face of this are two projecting lugs 69 which carry vertical bar guides 70. On the bar guides 70 are ver-

tically slidable tubular members 71 which are fixed at their lower ends in the cross head 64 and at their upper ends in a cross yoke 72. The tubular members are further guided by a pair of apertured lugs 73 which are also carried by the hot plate 20. The yoke 72 is actuated through yielding connections at each side of the machine from a corresponding one of the rods 37. The rod 37 passes through an eye 74 on one arm 75 of a bell crank. Stop lugs 76 and 77 on the rod 37 engage the arm 75 and actuate the same. Each arm 75 is journaled at 78 on the yoke 19 and has rigidly connected therewith another arm 79 which has a pin and slot connection 80, with the upright rods 81. The rods 81 are slidable through lugs 82 on the cross yoke 72, and yielding connections between the rods 81 and the yokes 72 are afforded by the compression springs 83 and 84 mounted above and below the lugs 82 and adjustably stressed by the nuts 85 and 86.

The parts are so timed that the die part 24 engages the die part 23 before the rod 37 reaches its leftward limit of motion and before the goose neck 60 has been raised to its upper limit of motion. The rods 37 then continue to move to the left, stressing the springs 43 and increasing the closing pressure on the two die parts. This continued motion causes the goose neck nozzle 62 to engage the plate 63 and force it against the lower face of the die parts 23 and 24, which are at this time in close contact with each other. This occurs before the rod 37 has completed its leftward motion, and the final portion of the motion is used to actuate the air mechanism which establishes pressure within the goose neck 60 and forces the molten metal from the goose neck into the die by way of the nozzle plate 63.

The air so used is displaced by a piston in the cylinder 53 and this piston is actuated by compressed air admitted behind it from a pressure line.

The mechanism now to be described involves the major portion of the present invention. The die actuating mechanism and the goose neck actuating mechanism, generally speaking, are ancillary features claimed elsewhere and are here described only in the interest of a full and adequate explanation of the invention.

The cylinder 53 contains a piston 90 to which is fixed a piston rod 91. The cylinder is closed at both ends by heads, and at the forward end has a port 93 which extends to a cup shaped recess 94 formed in a projecting nipple. With this coacts the convex nipple 95 having a registering port which communicates with the interior of the goose neck 60. The nipple 95 seals in the recess 94 when the goose neck is drawn up with its discharge nozzle 62 in engagement

with the nozzle plate 63. When the piston 90 moves to the right it displaces air from the cylinder through the port 93 and into the goose neck 60.

5 The rod 91 extends through a stuffing box 96 and is connected to a cross yoke 97 by means of which the piston is retracted and also controlled in its movements. The yoke 97 is connected by two rods 98 with a yoke 99 having two guide bearings 100 which slide each on a corresponding one of the two rods 37 near the rear ends thereof. This yoke 99 is provided at each end with an extension 101, to each of which is bolted a 15 corresponding piston rod 102 of an oil retarding device. Each rod 102 is connected to a corresponding piston 103, and each such piston works in a corresponding cylinder 104 supported by a bracket 105 on the base 20 member 52. The cylinders contain oil.

A by-pass pipe 106 connecting the opposite ends of the cylinder 104 is controlled by a throttling valve 107. By adjusting the valves 107 it is possible to determine the 25 rate of movement of the piston 90 to the right. Its motion to the left is mechanically effected and is relatively so slow that the oil checking devices are then without material effect.

30 Each of the bearing members 100 is formed with a vertical guideway in which is mounted a shouldered latch pin 108. When the rods 37 move to their extreme right hand positions, which they do after the piston 35 90 has been forced to the right hand limit of its motion, the ends of the rods 37 overrun the latch pins 108 and these pins drop and engage the ends of the rods, so that on the return movement of the rods 37 to the 40 left they displace the piston 90 also to the left. As stated, this motion takes place slowly, so that the oil checks have no appreciable effect.

45 As the piston reaches its left hand limit of motion and before the goose neck 60 has been fully raised, the latch members 108 are raised so as to disconnect the yoke 99 from the rods 37. This is effected by an inclined cam 109 formed on the end of a 50 bar which is adjustably mounted at 110 in a bracket 111. This bracket 111 is supported on the rear cylinder head and in turn supports the valve mechanism now to be described.

55 The function of this valve mechanism is to admit air to the space to the left of the piston 90 to force this piston to the right, and thereafter to vent the space to atmosphere to permit the piston 90 to be returned without resistance to its initial position as 60 just described. Briefly stated, the rods 37 at their limit of motion to the left, and consequently during the dwell period, close an exhaust port leading from a space to the left of the piston 90 and open an admission port leading to such space from any

suitable source of pressure fluid. In all other positions of the rods 37 the exhaust valve is open and the inlet valve is closed.

The inlet valve mechanism is shown in Fig. 4 and is actuated by rod 37 on that side of the machine which is nearer to the observer in Fig. 1. The inlet valve chest is shown at 112, and the air supply line at 113, see Figs. 3, 4 and 8. The space within the valve chest is divided into two 75 parts by a valve seat 114 with which coacts the poppet valve 115, which tends to seat under pressure entering through the pipe 113. To the stem of the valve 115 is connected a rod 116 mounted in a guide 117, and on the rod 116 there is threaded at 118 an adjustable extension 119, with which the end of the rod 37 collides after the corresponding latch 108 is released.

The motion of the rod 37 after this latch is released unseats the valve 115 and allows pressure fluid to enter by way of valve 115, chamber 120, pipe 121, pipe 122, and port 123, to the space at the left end of cylinder 53. The threads 118 permit the extension 119 to be adjusted so as to time the inlet valve. The exhaust valve is essentially similar but reversed in arrangement. The exhaust valve chest is shown at 124 and the exhaust pipe leading to the atmosphere at 125.

Within the chest 124 is a seat 126 with which the exhaust valve 127 coacts. This valve is reversely seated with respect to the inlet valve, and its stem is connected to a sliding yoke 128 which is urged in a valve opening direction by two compression springs 129. The yoke 128 carries fixed to it a rod 130 which slides in a bearing 131, and which carries threaded to it at 132 an adjustable extension 133. The adjustment of this extension allows the closing of the exhaust valve to be timed, and the extension 133 is directly in the path of the end of that rod 37 which is farthest from the observer in Fig. 1. The inlet and exhaust valves are timed so that the exhaust valve closes approximately at the time the inlet valve opens. The valve chest 124 is connected by a pipe 134 with the pipe 122 already described, and hence controls a passage leading from the left end of the cylinder 53 to the atmosphere.

The mechanism so far described provides a complete operative structure which functions as follows: Assume that the melting pot is filled with metal, that the air supply pipe 113 is connected to a suitable source of air under pressure, and that the cranks 29 are horizontal and to the right. Under these conditions the air inlet valve is closed, the piston 90 is in its extreme right hand position, the dies are wide open, and the rods 37 are at the right hand limit of motion, i. e., far enough to engage behind the

latches 108. The goose neck 60 is submerged in the molten metal and is filled therewith.

As the cranks 29 revolve the die carrier 22 moves to the left and the goose neck 5 starts to rise. The die part 24 engages the fixed die part 23 and shortly after this has occurred the goose neck 60 forces its nozzle 62 against the nozzle plate 63 and clamps the latter against the lower faces of the die. 10 However, before this occurs the latches 108 will have been released by the cams 109, so that the piston 90 comes to rest before the nipple 95 seals in the recess 94. This eliminates any possibility that the motion of the 15 piston will draw molten metal from the goose neck into the cylinder.

Shortly after the dies have closed and the piston 90 has come to rest the nozzle 62 on the goose neck engages the nozzle plate 63, 20 effecting a tight seal between the nozzle, the nozzle plate, and the bottom of the die. At the same time, the nipple 95 engages in a recess 94 and conditions are established for shooting the casting. A slight further movement of the rods 37 closes the exhaust valve 127 and opens the inlet valve 115, whereupon air pressure is admitted from the line 113 to act against the rear of the piston 90 and to force it to the right at whatever 25 speed is permitted by the adjustment of the valves 107. The rods 37 remain at their left hand limit of motion for a considerable period, during the dwell caused by the cam 31 intended to allow the casting to freeze 35 in the mold. At the end of this period the rods 37 again start to the right, closing the inlet valve and opening the exhaust valve, so that the piston is once more free to be forced back to the left in the ensuing cycle 40 of operations.

The machine just described is entirely operative, but a more refined operation can be secured by the addition of certain optional details now to be described. The first 45 of these is the throttling vent valve whose casing 140 is threaded into the goose neck 60, see Figs. 10 and 11. A needle valve 141 adjustable by a milled head 142 and threaded in the body 140, affords a minute adjustable vent port leading from the goose neck 50 to the atmosphere.

In certain cases it has been found desirable to reduce the impact of the entering air upon the metal in the goose neck at the 55 beginning of the piston movement, and this throttling vent valve has been found highly effective in overcoming difficulties encountered. Its utility varies with the nature of the mold, and it need not always be used.

The second refinement is a valve mechanism which functions to release all pressure from the goose neck at any desired time in the cycle, and in any event before the goose neck starts to lower. A pipe 150 leads from 65 the port 93 to a valve chamber 151, see Figs.

3, 4 and 10. Within the chamber 151 is a poppet valve 152 which is seated by pressure in the chamber 151 and also by a spring 153. The valve 152 controls the flow to a vent port 154. It is forced open at the proper time by a thrust rod 155 which is urged to the right by a spring 156, and which is arranged to be forced back by one arm 157 of a bell crank pivoted at 158 on the housing 17. The other arm 159 of the bell crank carries a roller 160 which runs on a cam 161 adjustably mounted on the shaft 28. This cam is ordinarily arranged to open the valve 152 shortly after the piston 151 reaches the right hand limit of its motion, and maintain it open at least long enough to insure the complete venting of the pressure.

The use of the piston has a particular advantage, in that it permits very rigid control of the rate of air admission to the goose neck, and in that the air injected to the goose neck is taken directly from the space above the melting pot. Air taken from above the melting pot has a reduced oxidizing tendency, and moreover is heated.

Approximately equivalent results can, however, be secured by omitting the piston 90 and its connected parts, that is, generally speaking, the rod 91, the yoke 97, rods 98, and the yoke 99 with the connected latches and oil cylinder mechanism. In such case the inlet and exhaust valves 115 and 127 handle the admission of air directly from the air line 113 to the goose neck. The use of the bleed valve shown in Fig. 1 and of the positive vent valve 152 is optional, but is here probably more desirable even than when the piston is used, because of the modifying characteristics which they possess.

What is claimed is:

1. The combination with a die casting machine of the type in which the molten metal is forced into the die by gas under pressure entering through a pressure connection, of a movable abutment interposed in said connection and controlling flow therethrough; and means for regulating the movement of said abutment.

2. The combination with a die casting machine of the type in which molten metal from a supply thereof is forced into the die by gas under pressure entering through a pressure connection, of a movable abutment interposed in said connection and controlling flow therethrough; mechanical means for restoring said abutment to its initial position after movement by pressure; and means for causing said abutment to draw gases into said connection from adjacent the molten metal supply during such restoring movement.

3. The combination with a die casting machine of the type in which molten metal from a supply thereof is forced into the die

by gas under pressure entering through a pressure connection; of a movable abutment interposed in said connection and controlling flow therethrough; means for regulating the movements of said abutment when shifted by such fluid under pressure; mechanical means for restoring said abutment to its initial position after movement by pressure; and means for causing said abutment to draw gases into said connection from adjacent the molten metal supply during such restoring movement.

4. The combination with a die casting machine of the type in which molten metal is displaced from a pressure chamber into a die by pneumatic pressure; of an abutment periodically movable to establish such pressure; and elastic fluid pressure motor means for so moving said abutment.

20 5. The combination with a die casting machine of the type in which molten metal is displaced from a pressure chamber into a die by pneumatic pressure; of a piston periodically movable to establish such pressure; elastic fluid pressure motor means for so moving said piston; and an adjustable retarding means operatively connected with said piston.

6. The combination with a die casting machine of the type in which molten metal is displaced from a pressure chamber into a die by pneumatic pressure; of a piston periodically movable to establish such pressure; elastic fluid pressure motor means for so moving said piston; and a liquid displacing check device operatively connected to control the movements of said piston.

7. The combination with a die casting machine of the type in which molten metal is displaced from a pressure chamber into a die by gas pressure; of a constantly open bleed port acting to vent gas from said pressure chamber.

8. The combination with a die casting machine of the type in which molten metal is displaced from a pressure chamber into a die by gas pressure; of a constantly open bleed port acting to vent gas from said pressure chamber; and means for adjusting the effective area of said port.

9. In a die casting machine, the combination of a separable die; a pressure chamber movable into and out of connection with said die; an abutment movable to force air into said pressure chamber to expel metal therefrom into said die; means for operating said die, pressure chamber and abutment in timed relation; and means for venting said pressure chamber to atmosphere after said abutment has completed its working stroke and while said pressure chamber is in connecting relation with said die.

10. In a die casting machine the combination of a die including separable parts; a

pressure connection which when inactive is 65 open to atmosphere; a molten metal container; a pressure chamber movable between filling position beneath the molten metal, in which it is disconnected from the die and pressure connection, and an active position 70 in which it connects with the die and pressure connection simultaneously; a mechanism operable to establish pressure in said connection; a valve operable to exhaust pressure from said connection and chamber while 75 connected with each other; and actuating means arranged to close the dies, move the pressure chamber to connected position, operate the pressure establishing mechanism, 80 operate the exhaust valve while the pressure chamber is in connecting position, and then shift the pressure chamber to filling position and open the die.

11. In a die casting machine, the combination of a molten metal container; a separable die; a pressure chamber adapted alternately 85 to dip into said container and connect with the die; actuating means common to the die and pressure chamber for shifting them in timed relation, first closing the die and then 90 connecting the pressure chamber therewith; a pressure connection leading to said pressure chamber; a movable abutment interposed in said connection; and means operable by said actuating means and controlling 95 the admission of pressure fluid behind said abutment.

12. In a die casting machine, the combination of a molten metal container; a separable die; a pressure chamber adapted alternately 100 to dip into said container and connect with the die; actuating means common to the die and pressure chamber for shifting them in timed relation, first closing the die and then 105 connecting the pressure chamber therewith; a pressure connection leading to said pressure chamber; a movable abutment interposed in said connection; means operable by 110 said actuating means and controlling the admission of pressure fluid behind said abutment; and means for regulating the movement of said abutment under pressure by said fluid.

13. In a die casting machine, the combination of a molten metal container; a separable die; a pressure chamber adapted alternately 115 to dip into said container and connect with the die; actuating means common to the die and pressure chamber for shifting them in timed relation, first closing the die and then connecting the pressure chamber therewith; a pressure connection leading to said pressure chamber; a movable abutment interposed in said connection; means operable by 120 said actuating means and controlling the admission of pressure fluid behind said abutment; and means operable by said actuating 125 means in its die closing movement serving

to retract said abutment and then release the same.

14. In a die casting machine, the combination of a molten metal container; a separable die; a pressure chamber adapted alternately to dip into said container and connect with the die; actuating means common to the die and pressure chamber for shifting them in timed relation, first closing the die and then connecting the pressure chamber therewith; a pressure connection leading to said pressure chamber; a movable abutment interposed in said connection; means operable by said actuating means and controlling the admission of pressure fluid behind said abutment; means for regulating the movement of said abutment under pressure by said fluid; and means operable by said actuating means in its die closing movement serving to retract said abutment and then release the same.

15. In a die casting machine, the combination of a molten metal container; a separable die; a pressure connection; a pressure chamber adapted alternately to dip into said container and to connect with said die and connection simultaneously; actuating means common to the die and pressure chamber for shifting them in timed relation, closing the die and connecting the pressure chamber; a movable abutment interposed in said pressure connection; and means operable in timed relation by said actuating means to admit pressure fluid behind said abutment and thereafter vent the pressure chamber, both while the latter is in connecting position.

16. In a die casting machine, the combination of a molten metal container; a separable die; a pressure connection, a pressure chamber adapted alternately to dip into said container and to connect with said die and connection simultaneously; actuating means common to the die and pressure chamber for shifting them in timed relation, closing the die and connecting the pressure chamber; a movable abutment interposed in said pressure connection; means for regulating the movement of said abutment; and means operable in timed relation by said actuating means to admit pressure fluid behind said abutment and thereafter vent the pressure chamber, both while the latter is in connecting position.

17. In a die casting machine, the combination of a molten metal container; a separable die; a pressure connection, a pressure chamber adapted alternately to dip into said container and to connect with said die and connection simultaneously; actuating means common to the die and pressure chamber for shifting them in timed relation, closing the die and connecting the pressure chamber; a movable abutment interposed in said pressure connection; means operable in timed

relation by said actuating means to admit pressure fluid behind said abutment and thereafter vent the pressure chamber, both while the latter is in connecting position; and means shiftable by the die actuating means as the dies close, serving to restore said abutment.

18. In a die casting machine, the combination of a molten metal container; a separable die; a pressure connection, a pressure chamber adapted alternately to dip into said container and to connect with said die and connection simultaneously; actuating means common to the die and pressure chamber for shifting them in timed relation, closing the die and connecting the pressure chamber; a movable abutment interposed in said pressure connection; means operable in timed relation by said actuating means to admit pressure fluid behind said abutment and thereafter vent the pressure chamber, both while the latter is in connecting position; and an adjustable valve controlling an independent vent from said pressure chamber.

19. In a die casting machine, the combination of a die having a movable part; a pressure chamber movable into and out of connecting relation with said die; reciprocating actuating means having yielding driving connections with the movable die part and the pressure chamber; a piston arranged to force air into said chamber; a pressure line; valve mechanism controlling the admission of fluid from said pressure line against said piston to move the same in air forcing direction; means whereby said actuating means operates said valve mechanism as the former reaches its limit of motion in die closing direction; a latch connection between said actuating means and piston when the latter moves in die closing direction for retracting the piston; and means for releasing said latch connection before said valve mechanism is operated.

20. In a die casting machine, the combination of a die having a movable part; a cylinder having a discharge port at its forward end; a pressure chamber movable into and out of simultaneous connection with said port and the die; reciprocating actuating means having yielding connections arranged first to close the die and then connect the pressure chamber, and to operate reversely in the reverse order; a piston in said cylinder; a pressure line leading to the rear end of said cylinder; valve mechanism controlling the admission of pressure from said line to the rear end of said cylinder, said mechanism being operable by said actuating means at the limit of its motion in die closing direction; a latch connection between said actuating means and piston arranged to move the latter rearwardly as the die is closed; and means for releasing said latch before the pressure

chamber reaches connecting position and prior to the operation of said valve mechanism.

21. In a die casting machine, the combination of a die having a movable part; a cylinder having a discharge port at its forward end; a pressure chamber movable into and out of simultaneous connection with said port and the die; reciprocating actuating means having yielding connections arranged first to close the die and then connect the pressure chamber, and to operate reversely in the reverse order; a piston in said cylinder; means for controlling the movements of said piston; a pressure line leading to the
- rear end of said cylinder; valve mechanism controlling the admission of pressure from said line to the rear end of said cylinder, said mechanism being operable by said actuating means at the limit of its motion in die closing direction; a latch connection between said actuating means and piston arranged to move the latter rearwardly as the die is closed; and means for releasing said latch before the pressure chamber reaches connecting position and prior to the operation of said valve mechanism. 20 25

In testimony whereof I have signed my name to this specification.

TORBJORN CONRAD KORSMO.
